Application December 30, 1953, Serial No. 401,172

1 Claim. (Cl. 254—186)

This invention relates to a winch and more particularly to a winch of the type adapted to be mounted on a service truck for raising or lowering a load adjacent the rear end thereof.

A primary object of the invention is to rotate a winding drum during the lifting of a load and to regulate the speed of retrograde motion of the winding drum during the period that the load is being lowered.

Another object is to insure the smooth operation of the winding drum during both the winding or unwinding of a cable relative thereto.

The above and other objects may be attained by employing this invention which embodies among its features a differential having drive axles mounted to rotate about a common axis, brake drums carried by the drive axles for rotation therewith, brake shoes carried by the differential adjacent the brake drums for engagement with said brake drums to arrest rotation thereof, a winding drum mounted adjacent one of the brake drums for rotation about the common axis, a coupling carried by the winding drum and bolted to the adjacent brake drum for causing the winding drum to rotate in unison with said brake drum, and means carried by the differential and operatively connected to the brake shoes for selectively moving said shoes into engagement with their respective brake drums and arresting rotation of one or the other of the drive axles.

Other features include hydraulically energized means carried by the differential and operatively connected to the brake shoes for moving the brake shoes into frictional contact with the brake drums to arrest rotation thereof, and manually controlled hydraulic means operatively connected to the hydraulically energized means for selectively energizing said last named means and arresting rotation of a selected drum.

In the drawings:

Figure 1 is a side elevation of a service truck showing this improved winch mounted thereon;

Figure 2 is an enlarged top plan view partially in section of the winch; and

Figure 3 is a sectional view taken substantially on the line 3—3 of Figure 2.

Referring to the drawings in detail, a service truck designated generally 10 is equipped with a conventional boom 12 which projects upwardly and rearwardly beyond the rear end of the service truck 10, as will be readily understood upon reference to Figure 1.

My improved winch designated generally 14 comprises a bed frame 16 upon which is supported longitudinally spaced parallel cross beams 18 and end members 20 and 22. Carried by and extending between the end member 22 and the next adjacent cross beam 18 is a supporting channel 24 having longitudinally spaced openings 26 extending therethrough and carrying longitudinally spaced eyes 28, the purpose of which will hereinafter appear.

Carried by the end bar 20 and the next adjacent cross beam 18 are straps 30 which serve to clamp the axle housing extensions 32 of a differential case designated gen-

erally 33 to the frame 16 for rigidly supporting the differential case in position on the frame 16. A suitable block 34 is carried by the frame 16 and extends upwardly therefrom between the cross member 18 and the end bar 20 and carried by the block 34 is a strap 36 which engages the propeller shaft housing 38 of the differential 33. A propeller shaft 40 is mounted in the housing 38 for rotation about its longitudinal axis and is connected within the interior of the differential housing 38 through a conventional train of gears 42 to axle shafts 44 and 46 which extend through the extensions 32 and carry adjacent their ends remote from the gear train 42 brake drums 48 and 50, respectively.

Mounted for rotation in bearings 52 about an axis which aligns with the axis of the axle shafts 44 and 46 is a shaft 54 carrying intermediate its ends a spool or winding drum 56 upon which a cable 58 is wound according to the direction of rotation of the shaft 54. Integral with the shaft 54 adjacent the drum 50 is a flanged, cup shaped coupling 60, the outwardly directed flange 62 is provided with circumferentially spaced openings which are adapted to register with circumferentially spaced internally screw threaded recesses formed in the drum 50 for the reception of screws 64 which pass through the openings in the flange 62 and enter the threaded openings in the drum 50 to cause the spool or winding drum 56 to rotate in unison with the drum 50. The coupling opens toward drum 50 and encloses the outer end of the axle shaft 46, with shaft 54 connected to the closed end of the coupling in coaxial alignment with axle shaft 46. Carried by the differential housing 33 adjacent the ends of the tubular arms 32 are closure discs 66 which serve as dust caps to exclude dust and dirt from the interior of the drums 48 and 50, and carried by the disc 66 which closes the drum 48 is a conventional brake shoe 68, the expansion of which is governed by a conventional hydraulic cylinder 70. The differential housing, arms 32, and discs 66 comprise, with the elements 16, 18, 20, 22, and 24, a stationary support structure. A similar brake shoe 72 is carried by the disc 66 which closes the open side of the drum 50 and the expansion of the shoe 72 into contact with the drum 50 is controlled by a conventional hydraulic cylinder 74. Mounted in one of the openings 26 in the frame member 24 is a hydraulic master cylinder 76 and a similar master cylinder 78 is mounted in the adjacent opening in the member 24. A tubular conduit 80 communicates with the master cylinder 78 and with the brake shoe expanding cylinder 74 and a similar tubular conduit 82 establishes communication between the master cylinder 76 and the brake shoe actuating cylinder 70. It will thus be seen that by the manipulation of the plunger within the master cylinder 78, the brake shoe 72 may be expanded into engagement with the drum 50 to arrest rotation of the spool or winding drum 56, whereas upon the manipulation of the plunger of the master cylinder 76, the brake shoe 68 within the drum 48 will be expanded into contact with the drum to arrest rotation of the axle shaft 44 and cause any rotary motion imparted to the propeller shaft to be transmitted to the axle shaft 46 and hence through the drum 50 and coupling 60 to the spool or winding drum 56. Carried by and extending between the end bar 22 and adjacent cross bar 18 in spaced parallel relation with the supporting member 24 is a shaft 84 upon which levers 86 and 88 are mounted to rock. These levers are coupled to the plungers of the cylinders 76 and 78 so that the hydraulic cylinders 70 and 74 may be manipulated from a person stationed adjacent the hand levers 86 and 88.

Carried by the frame 16 at any convenient location is a prime mover designated generally 90 which is coupled with a conventional speed reduction gear 92, the drive shaft 94 of which carries a pulley 96 and carried by the

propeller shaft 40 adjacent the end thereof remote from the gearing 42 is a drive pulley 98 which is coupled to the pulley 96 by endless belts 100. It will thus be seen that with the prime mover 90 in operation, the propeller shaft 40 will be driven to impart rotary motion to the gears 42 of the differential. When it is desired to rotate the spool or winding drum 56, the hand lever 88 is moved to expel hydraulic fluid from the cylinder 76 to the conduit 80 and into the cylinder 70 to expand the brake shoes 68 into engagement with the drum 48. It will thus be seen that the brake shoe 68 will move into engagement with the brake drum 48 to arrest rotation of the shaft section 44 and cause the power transmitted to the gearing 42 through the propeller shaft 40 to be taken up by the shaft section 46 and through the drum 50 to be transmitted through the medium of the coupling 60 to the winding drum or spool 56. This will cause the cable 58 to be wound upon the winding drum and cause any weight carried by the end of the cable remote from the winding drum to be elevated toward the boom 12. When it is desired to lower the load, the hand lever 86 is moved to expel fluid from the cylinder 78 through the conduit 80 to the cylinder 74 to cause the brake shoes 72 to expand into contact with the drum 50 and simultaneously the hand lever 88 is moved to withdraw fluid from the cylinder 70 and permit the shoe 68 to disengage the drum 48. With the shoe 72 frictionally engaging the drum 50, the speed of descent of the load on the cable 58 may be governed, or the descent of the load can be completely arrested according to the pressure of the fluid within the cylinder 78.

While in the foregoing there has been shown and described the preferred embodiment of this invention, it is to be understood that minor changes in the details of construction, combination and arrangement of parts may be resorted to without departing from the spirit and scope of the invention as claimed.

What is claimed is:

A winch comprising a supporting structure; a pair of axle shafts having inner ends in spaced relation, said axle shafts being rotatably mounted on said structure; brake drums connected to the outer ends of the respective axle shafts for rotation therewith; brake shoes carried by said structure for arresting rotation of the respective drums and shafts; a spool rotatably mounted on said structure; a cable wound upon the spool; means connecting the spool and one drum for joint rotation, both drums being mounted on said structure in positions elevated above and wholly out of contact with a supporting surface over which the structure is disposed, for rotation of the drums free of restraint by said surface, the spool including a shaft coaxial with the axle shafts and lying wholly beyond the outer end of the axle shaft connected to said one drum, said means comprising a cup shaped coupling formed open at one end, said one end of the coupling opening toward said one drum and being formed with an outwardly directed peripheral flange secured to said one drum, the coupling enclosing the outer end of the axle shaft connected to said one drum, and the spool shaft being rigidly connected to the coupling at the closed end thereof; a differential drivingly connected to the respective axles; means connected to the differential for driving the same; and means mounted on said structure and connected to the respective shoes for shifting each shoe into engagement with its associated drum independently of the other shoe.
